CONCRETE WALL FORM

Robert R. Leggett, Sr., Fort Worth, Tex., assignor
of forty-five per cent to Clyde Averitt, Fort
Worth, Tex.

Application August 29, 1941, Serial No. 408,792

6 Claims. (Cl. 25—131)

This invention relates to collapsible forming apparatus for concrete foundations, walls, and the like, and it has particular reference to apparatus embodying adjustable standards and supports adapted to retain vertically arranged and spaced temporary walls forming channels to receive poured concrete and its principal object resides in the provision of an arrangement of parts designed to afford a concrete foundation and wall form capable of angular and vertical adjustments whereby various conditions and circumstances can be economically and expeditiously met resulting in a great saving of time and expense usually attendant upon such operations.

Another object of the invention resides in the provision of a form assembly embracing features enabling the same to be operatively arranged quickly and with a minimum of effort and embodying adjustable features adapting the assembly to be arranged along inclined or irregular surfaces thus permitting the erection of a foundation or wall whose upper plane is horizontal irrespective of the contour of the earth's surface over which the assembly is disposed.

A still further object of the invention is manifested in the provision of a unitary assembly embodying a plurality of adjustable standards and brackets capable of vertically supporting the forming walls of the assembly having pivotal connections with the said standards permitting vertical angular adjustments of the said forming walls with respect to the said standards conformably adapting the said forming walls to the inclinations or irregular conformations of the earth's surface, yet allowing the said standards to remain in vertical position with respect to the inclination of the said forming walls.

An object of the invention is that of providing both right angle, or corner supports, and obtuse angle supports for the said forming walls and adapting the latter to be hingedly connected to the said supports whereby angular variations can be accomplished in the linear course of the said wall or foundation, and at once, allow for the vertical pivoting of the said forming wall to the said standard providing for both vertical and lateral adjustments of the said forming wall.

Broadly, the invention seeks to comprehend the provision of a form assembly for foundations, walls, and the like, comprising an arrangement of elements adopting the same to be employed under practically all circumstances and conditions without regard to height or thickness of the wall, or the contour of the earth's surface over which the same is constructed, and providing a

collapsible assembly adapted to be moved from one structure to another with a minimum of effort and which is capable of saving both material and labor, as well as time.

5 While the foregoing objects are paramount, other and lesser objects will become manifest as the description proceeds when taken in connection with the appended drawings wherein:

Figure 1 is a fragmentary perspective illustration of the assembly showing an adjustable right angle standard and a joint assembly.

Figure 2 is a fragmentary plan view illustrating both right angle and obtuse angle assemblies, as well as a joint assembly, for the forming walls.

Figure 3 illustrates, in perspective, a right angle connecting plate adapted to be pivotally connected to a wall assembly.

Figure 4 is a perspective illustration of an adjustable angular support having the pivotal connecting plate hingedly connected therewith and which is especially adapted to the obtuse angle construction illustrated in Figure 2.

Figure 5 shows the invention fragmentarily, as the same is applied to an inclined surface, and illustrating the manner in which the joint plates and angular or corner plates are pivotally connected to the wall sections and showing, in dotted lines, the grade level or top of the foundation or wall structure formed by the assembly.

30 Figure 6 is an elevational illustration of one of the wall standards having an adjustable base adopting the same to be adjusted to a vertical position, as illustrated in dotted lines, on irregular surfaces.

35 Figure 7 fragmentarily illustrates, in perspective, the extensibly adjustable brace member for the standards shown particularly in Figures 1 and 6, and

40 Figure 8 is a front perspective view of the corner standard assembly showing the pivotal connection with the wall sections.

45 Conventional methods employed in the construction of concrete walls and foundations often result in great waste due to the fact that materials so employed are, for the most part, useless for other purposes when the structures are completed. Much time is also required, and consequently a great expense is entailed, in the construction of forms by conventional methods since the materials used therein must be cut and fitted to the particular job and afterwards thrown away with a resulting unnecessary loss of labor and much of the materials. A primary object of the invention, therefore, is that of providing an arrangement whereby even unskilled workmen,

under the supervision of one skilled in the art, can assemble the form with due regard to accuracy and quality of workmanship at a great saving of time and expense.

The invention, therefore, comprises a plurality of standards or uprights 1 having hinged laterally extending bases 2 each adapted to be bolted, or otherwise secured, to wooden member 3 of such dimension as 2" x 4", 2" x 6" material, and the like. Both the standards 1 and the bases 2 are preferably formed from angle iron to insure sufficient strength and to provide projecting flanges to which the bases 4 are secured at each end, as illustrated in Figure 6. The braces 4 are extensibly adjustable, being comprised of a pair of lapping members *a* and *b* having their meeting surfaces corrugated at *c*, as illustrated in Figure 7, and each are slotted at *d* to receive a bolt 5 on which a wing nut 6 is threaded. In this manner, and by reason of the fact that the member 4 is pivotally connected at *e* and *f* to the upright standard 1 and the base member 2, and by reason of the hinged connection 7 between the members 1 and 2, the standard 1 can be maintained in a vertical position irrespective of the position of the base member 2, as illustrated in dotted lines in Figure 6.

All of the vertical standard assemblies, comprising the upright members 1 and the base members 2, and their associated elements, are preferably uniform in structure, but may vary in height from approximately 18" to several feet in order that they may be adaptable to walls of varying height, as illustrated in Figure 5. Each of the standard members are adapted to support the walls at intervals which may vary according to conditions and the particular requirements on each structure.

The wall units comprise a plurality of preferably tongued and grooved pieces of lumber 8, which may vary in width but of conventional dimensions so that the walls may be of different heights, in the manner illustrated in Figure 5. Each of the pieces 8 are provided with apertures so that metal cleats 9 can be secured thereto at proper intervals to sufficiently reinforce the wall, as illustrated in Figures 1 and 5. The ends of each of the pieces 8 are slotted at 10 to receive the bolts 11 in the connecting plate 12 which will be presently described.

At each of the joints between the wall sections a connecting plate 12 is provided which is pivotally secured to one of the standards 1 through the medium of a bolt 13 arranged centrally through the member 12, as illustrated particularly in Figure 1. Each of the members 12 comprises a metal plate adapted to be vertically positioned and formed with outwardly extending integral flanges 14 uniformly spaced from the sides of the plate 12 forming substantially rectangular receptacles on each side thereof for the ends of the wall boards 8 when a metal cleat 15 is applied exteriorly of the assembly, as illustrated in Figure 1. Both the members 12 and 15 are provided with a plurality of apertures 16 to receive bolts 11 which extend through the slots 10 of the wall boards 8 in the manner previously described.

As the wall sections are assembled, therefore, the vertical standards 1 are positioned along the excavation for the foundation and spaced at proper intervals and the members 12 are secured thereto by the bolts 13 so that the members 12 can pivot on the standards 1. The wall boards 8

are assembled in sections, their height being determined by the number of the pieces employed, and secured together by the cleats 9. Such sections are joined to the members 12 by inserting the ends thereof into the substantially rectangular receptacles formed on each side of the members 12 and the slots 10 receive the bolts 11 already in position in the member 12 and extending through the cleat 15 associated therewith. After the proper adjustment is made the bolts 11 can be tightened securing the ends of the wall sections to the joining plates 12 completing a rigid wall which may be pivotally adjusted, as illustrated in Figure 5, to the inclination of the earth's surface.

It is preferable that wherever joints in the wall section occur, and where the joining plates 12 are to be employed, one of the vertical standards 1 are assemblies, as shown in Figure 6, be installed opposite each of the joining plates 12, as shown in Figure 2, so that the plate members 12 may be staggered with respect to each other, the wall sections employed being of different lengths and terminating at different points along the linear course of the wall. This arrangement, however, is not essential to the proper operations of the device.

Both right angle and obtuse angle structures are provided, as illustrated in Figures 1, 3, 4, and 8, by which the linear course of the wall can be formed. The right angle assembly, providing for right angle corners in the foundations or wall structures, primarily comprises an angular plate 17, illustrated in Figure 3, having each of its extending flanges 18 formed with their edges inclined from the center toward each end defining a substantial triangle at the center of which is provided an aperture 19, adapted to receive a bolt 20 pivotally connecting the assembly to a wall section. At each joint of the wall section coupling plates 21, formed with a double bend 22 longitudinally thereof, are provided opposite flat plates 23 which combination form clevises by which the wall sections can be secured to the plates 17 through the medium of bolts 24 arranged through a series of apertures 25 in each of the members 21 and 23 so that the slots 10 in the ends of the members 8 will engage the bolts 24 in the same manner that the wall sections are connected to the joining plates 12 previously described. Figures 3 and 8 illustrate the manner in which the wall sections are pivotally connected to the corner or angle plates 17 thus permitting the forming walls to assume the position illustrated in Figure 5 while all of the standards remain in upright or vertical positions.

The angular plates 17 are secured to standards 26 which are formed substantially V-shaped in cross-section at their upper ends with angular flanges 27 conformable to the angular shape of the members 17, as illustrated in Figures 1 and 8, and are bolted or otherwise secured to the members 17. An extensibly adjustable brace member 4, illustrated in Figures 6 and 7, is pivotally connected to a projecting lug 28 secured to the upper ends of each of the standards 26 and to the flanged laterally extending base 2 at their lower ends, in the same manner as the member 4 is secured to the standard assembly illustrated in Figure 6. The base members 2 of the standards 26 is also hingedly connected at 7 to the latter.

It is obvious that either the structure illustrated in Figure 3 or the assembly shown in Figure 4 may be employed for the right angle formations

of the foundations, or wall structures, but it is preferable that the device shown in Figure 4 be used. This structure comprises primarily an angular member 29 formed with longitudinal flanges 30 each having plates 31 hingedly connected thereto through the medium of hinges 32, the plates 31 being formed with their outer edges inclined toward each end defining a substantial triangle at the apex of which, and intermediate the ends of the plates 31, are provided apertures 33 similar to the apertures 19 of the members 1, shown in Figure 3. The apertures 33 are adapted to receive the bolts 20 to which the clevis assemblies can be pivotally connected in the same manner as that illustrated in Figure 3. The clevis assemblies, as previously stated, are comprised of the plates 21, having the longitudinally extending double bend 22, and the flat plate 23 adapted to be positioned interiorly of wall structures, as illustrated in Figures 1 and 2, and to which may be secured the wall sections of the form through the medium of the bolts 24 engaging the notches 10 in the members 8.

It will be observed that in providing an obtuse angle, such as those illustrated in Figure 2, the device shown in Figure 4 can be adjusted to varying degrees of angulation while the structure illustrated in Figure 3 is rigid and is adapted only for a right angle position. It is preferable, therefore, that more of the structures illustrated in Figure 3 be provided since this device would be less expensive in construction than the assembly shown in Figure 4 and since it is obvious that fewer obtuse angles would be required in the construction of foundations and walls than the corner constructions for which the device illustrated in Figure 3 is particularly adapted.

To insure rigidity of the assembly constituting the plates 21 and 23, by which the wall sections of the forms are connected to the plates 17 and 31, locking devices 34 are provided which comprise substantially U-shaped clips having one leg pivoted at 35 to the exterior of the assembly, preferably to the plates 21, and having the other leg of the device over reaching the inside plate 23, as illustrated in Figures 1, 3, and 4, providing a latch adapted to be dropped over the assembly of the elements 21, 17, and 23 securing these members in cooperation with the bolts 20.

The forming walls are arranged to be variably spaced by lateral ties 36 which are provided at each end with a plurality of spaced apertures 37 through which bolts 38 are secured, in the manner illustrated in Figure 1, connecting the wall structures. The ties 36 are preferably secured to the upper ends of the standard assemblies 1 or to the members 26 where the ties 36 are employed across an angle as illustrated in Figures 1 and 2. Obviously, by reason of the plurality of apertures 37 on each end of the ties 36, the wall sections can be spaced according to the individual requirements.

The only difference between the inner and outer right angle forming assemblies, as illustrated in Figures 3 and 4, as the same are applied to the forming structure, is that the inner assembly as shown in Figure 1 is reversed in assemblage, the standard 26 supporting the angular plates 17 being positioned within the angle rather than exteriorly thereof, as illustrated in Figure 1, for the interior support of the right angle structures.

The foregoing is the preferred embodiment of the invention and it is not intended that the disclosure be limited to the specific details of material and construction since persons skilled in

the art may readily resort to certain changes and modifications from time to time and such changes and modifications which may be regarded as falling within the spirit and intent of the invention may also be regarded as falling within the scope of the appended claims.

What is claimed is:

1. A collapsible form assembly for forming building foundations and walls comprising, in combination, a plurality of sectional wall units of different lengths adapted for parallel spaced arrangement forming a channel, coupling plates secured to the ends of the said wall units at junctions thereof, corner plates formed with right angle flanges pivotally connected with the ends of certain of the said wall units, vertical standards having hinged base members extending laterally therefrom providing vertical supports for each of the said coupling plates and the said corner plates, each of the said standards having an extensibly adjustable brace member connecting the same with their said base members.
2. A portable and collapsible form assembly for concrete wall structures, in combination, a plurality of wall units of varying heights and lengths adapted for parallel alinement to form a channel for poured concrete, coupling plates secured to the said wall unit and providing interchangeable joints therefor, corner plates formed with right angle pivotal connections supporting the said wall units, vertical standards having laterally extending adjustable bases hingedly connected therewith, means providing a pivotal connection between each of the said standards and the said coupling plates and an extensibly adjustable brace member pivotally connected with each of the said standards and the said base members to adjust the latter with respect to the vertical planes of the said standards on irregular horizontal surfaces.
3. A forming assembly for poured concrete wall structures, in combination, a plurality of wall units of varying heights and lengths, wall couplings interchangeably connecting the said units forming parallel spaced walls defining a channel, angular corner couplings pivotally connected to the ends of the said walls adapting the latter to variable inclined planes, a plurality of vertical standards having hinged laterally extending base members providing vertical supports for the said walls at each of the said couplings, pivotal connections between the said wall couplings and the standards therefor and extensible brace members providing for the variable adjustment of the said base members compensating for variations in the inclinations of the earth's surface with respect to the vertical positions of the said standards.
4. In a forming assembly for concrete wall structures comprising wall units adapted to be associated in parallel spaced relation forming a channel, coupling plates connecting the said units, vertical standards pivotally connected with each of the said coupling plates adapting the said wall to variable inclinations of the supporting ground surface, base members hingedly connected to each of the said standards and extensible braces adjustably connecting the said standards with the said base members in conformity with the said ground surface with respect to the vertical positions of the said standards.
5. In a portable form assembly for concrete wall structures including a plurality of wall units adapted to be assembled in parallel and spaced walls forming a channel, wall couplings interchangeably joining the said units, corner cou-

plings providing angular pivotal joints for the said units; vertical supporting standards pivotally connected to the said wall couplings and similar members rigidly connected to the said corner couplings adapting the said walls to variable inclined planes and base members hingedly connected to each of the said standards adjustably retaining the same in a vertical plane.

6. In a portable form for concrete wall structures including wall units of varying heights and lengths and arranged in parallel spaced relation-

ship, interchangeable couplings connecting the said units, standards supporting the said walls having a pivotal connection with each of the said couplings, angular wall couplings forming corners for the said walls and having pivotal connections therewith, standards rigidly supporting each of the said angular couplings and adjustable bases hingedly connected with each of the said standards adapting the same to variable planes with respect to a vertical plane.
